BRUSH

Carl F. Craig, Winter Haven, Fla., assignor to
 Craig Easy-Clean Brush Company, Winter
 Haven, Fla., a corporation of Florida

Application December 12, 1931
 Serial No. 580,565

2 Claims. (Cl. 15—128)

My invention refers to brushes, especially paint brushes, and its primary object is to provide means for forcing a fluid through the butt and flag ends of the bristles for thoroughly cleansing the same.

Practise has demonstrated that paint brushes especially used for cement paints result in the paint adhering to the butt end of the bristles or fibers, whereby the same are quickly burned out, resulting in breaking off when the brush is thereafter used, said bristles thus, when not thoroughly cleansed, losing their life and flexibility. In other words, after the brush has been used with cement type of paint, it must be shortly thrown away and replaced.

Heretofore it has been difficult to clean brushes of this character, due to the fact that the paint adheres at the butt ends of the bristles and cannot be removed except in a crude manner by separating the rows of bristles and mechanically scraping the paint therefrom, and even this attempted cleaning is not effective.

Furthermore, when brushes are not thoroughly cleaned and thereafter paint of a different color is used, particles of the original color impregnate the bristles and will gradually work out and streak the job to which is being applied the second color. Hence, it will be understood that by employing my method of cleaning, considerable longer wear and life of the brush is had, and furthermore the bristles retain their flexibility, whereby better work is done and said brush can be quickly changed from one color to another to thus save time of the painter.

Specific objects of my invention are therefore to thoroughly cleanse the bristles from butt to flag end to prevent burning of the same when used with cement paints, to thus increase the life of a brush. To quickly cleanse the entire bristle whereby the brush is in condition to be quickly utilized for paint of a different color. To provide a brush having a removable handle for attaching a garden hose or pump wherein water, or other cleansing fluid, may be used. To provide a brush wherein the brush proper, in conjunction with the head, can be supplied separately from the handle. Thus one handle may be used for a series of brushes of different types.

Other specific objects are to provide a detachable handle of any desired shape to meet the requirements of the user. To eliminate the necessity of providing a pail for cleaning, and other manual operations. To provide means for introducing water, or other liquid, at or near the butt ends of the bristles, under pressure, to thus thor-

oughly cleanse the entire mass of bristles of any foreign matter.

With the above and other objects in view, the invention consists in certain peculiarities of construction and combination of parts, as will be fully set forth with reference to the accompanying drawing and subsequently claimed.

In the drawing:

Figure 1 represents a fragmentary sectional elevation of the brush embodying the features of my invention, the section being indicated by line 1—1 of Figure 2.

Figure 2 is a side elevation of the same, partly in section, as indicated by line 2—2 of Figures 3 and 4.

Figure 3 is a fragmentary bottom plan view of a brush embodying the features of my invention illustrating the fluid feed channels, and

Figure 4 is a detailed fragmentary view of the brush back element showing radial grooves or channels which are provided for supplying fluid under pressure to the brush bristles through a plurality of transverse apertures or channels.

Referring by characters to the drawing, 1 represents a back provided with a centrally disposed nozzle 2, which nozzle communicates with a plurality of radial or longitudinal channels 3—3. The nozzle has fitted therein a thimble 4 which is flanged at its upper end for engagement with a corresponding inwardly turned flange of an internally threaded coupling nipple 5. The nipple is seated against a washer 6, whereby the joint is made tight at this point, and there is also provided a flexible washer 7 within the nipple against which is seated the lower threaded end 8 of a handle 9 which may be of any desired shape. Thus it will be seen that the handle can be detached for cleaning purposes, and when this handle 9 is removed, an ordinary garden hose, having a threaded coupling end, may be substituted therefor, in which case the threaded end is fitted into the nipple 5, it being understood that this hose connection forms no part of my invention and therefore is not shown.

It is obvious that I may also, in place of using an ordinary garden hose in connection with the brush, in some cases employ a force pump, or other fitting, whereby a cleansing fluid of any desired consistency may be forced into the nozzle.

The lower channeled face of the head 1 has glued, or otherwise secured, thereto a plurality of spacing strips 10—10, the same terminating with V-shaped ribs from their lower surfaces to protect brush bristles in the usual manner. These V-shaped ribs are provided with trans-

110

versely disposed grooves 11 interrupting them at intervals, and communicating with the grooves 11 are a plurality of transverse apertures or channels 11', which channels, as best shown in Figure 2, communicate with longitudinal back panels 3.

The rows of bristles 12 are fitted and cemented between the spacing strips in the usual manner of brush construction, the butt ends of the outer 10 longitudinal rows of bristles being confined by the usual valance or ferrule 13, which may be of metal, leather, or other suitable material.

From the foregoing description it will be seen that after the brush has been used in paint of 15 any kind, and particularly paint containing cement, the same can be readily and thoroughly cleansed, both from the butt and flag or working ends of the bristles, by simply removing the handle and substituting therefor a fluid supply fitting, whereby fluid under pressure is forced 20 through the nozzle 2, longitudinal channels 3, grooves 11 and cross grooves 11', whereby said fluid is thoroughly broken up into multiple jets or streams, to thus impregnate the bristle butts 25 to wash or cleanse the same, and, also, as the fluid flows downwardly through the brush bristles, they may be worked by hand so as to cleanse the entire length of bristle from butt to flag end. It will be observed that this cleansing operation can 30 be effected in the shortest possible time, by the interchangeable parts, as just described. The brush, when thus cleansed can be suspended in any suitable way for drying out, or it may be immediately used in the event the operator desires 35 to work with another color.

From the foregoing it will be seen that the brush is quickly cleansed either for storing away or for interchangeability of color without any loss of time, and, owing to said thorough cleansing 40 the brush, as a whole, can be operated with

efficiency throughout its long life, whereas under old conditions when cement paint was used, the bristles would soon become burned or weakened in such manner that they would break out at the butt ends, or slough off, due to the injurious effects from the continual partial cleansing by the old method of so doing.

While I have shown and described one exemplification of my invention minutely as to details of construction, it is understood that I may vary structural features of the brush within the scope of the claims.

I claim:—

1. A brush comprising a brush head including inner and outer abutting sections, means connecting the sections together, brush tufts carried by one of said sections, said last named section having a plurality of outlet flushing channels adjacent to the brush tufts, the inner face of the other section having distributing channels communicating with the outlet flushing channels and a common port communicating with said distributing channels, a detachable handle for normally closing said common port, and means carried by the walls of the port for receiving a hose when the handle is removed.

2. A brush embodying a head, a nozzle extending therefrom, the same comprising an upper section, a lower section secured to the upper section and spaced therefrom to form channels communicating with the nozzle, said lower section including a plurality of strips having transverse apertures in communication with the channel, rows of bristles secured between the strips, and a valance extending from the upper section engaging the outer row of bristles, whereby said outer row is secured between the valance and juxtaposed face of one of the lower section strips.
